UNITED STATES PATENT OFFICE.

WILLIAM HENRY KIDDER, OF COLCHESTER, VERMONT.

BOX-COVER SUPPORTER AND HOLDER.

SPECIFICATION forming part of Letters Patent No. 769,481, dated September 6, 1904.

Application filed April 18, 1903. Serial No. 153,186. (No model.)

To all whom it may concern:

Be it known that I, WILLIAM HENRY KIDDER, a citizen of the United States, residing at Colchester, in the county of Chittenden and State of Vermont, have invented a new and useful Box-Cover Supporter and Holder, of which the following is a specification.

This invention relates to a box-cover holder, and particularly to a device adapted to support the cover in a plurality of positions relative to the box.

The invention has for an object to provide a plate having at one end means for engaging a cover and at the opposite end a plurality of slots or equivalent means adapted to adjustably engage the edge of a box.

Other and further objects and advantages will be hereinafter set forth, and the novel features thereof defined by the appended claims.

In the drawings, Figure 1 is a perspective of the holder; Fig. 2, a similar view of a modified form of the invention. Fig. 3 is a perspective showing the application of the holder to a box in one position, and Fig. 4 a similar view showing another adjustment of the holder.

Like letters of reference refer to like parts in the several figures of the drawings.

Referring to Fig. 1, the letter A designates a plate of metal or other suitable material, preferably formed from a single blank and provided at one end with means for engaging a cover and at the opposite end with a plurality of means for engaging a portion of a box-body. These engaging means preferably comprise slots having tongues at the opposite sides thereof—for instance, a cover-engaging slot A' at one end, having tongues *a* and *b* at

opposite sides thereof. These tongues may also be bent away from the plate at an angle thereto, as shown in Fig. 1, or upon a curved line, as shown in Fig. 2. The box-engaging end of the holder may likewise be provided with a series of slots A², disposed in different positions relative to the slot A' and formed within the enlarged portion A³ of the holder, thus providing tongues upon the opposite sides of each slot. Three of these box-en-

gaging slots are shown in Fig. 1, thus adapting the cover for adjustment into three different positions; but it will be apparent that the number of slots may be varied.

In the modified form of the holder shown in Fig. 2 the plate B is curved and the cover-engaging slot B' formed at one end thereof with the tongues *a'* and *b'* at opposite sides thereof. In this form of the invention two box-engaging slots B² are provided in the enlarged end B³ of the plate.

In the application of the invention it will be seen that the cover may be adjusted at different inclinations relative to the box by engagement of the different box-holding slots, while the tongues at the cover-holding slot 65 permit engagement with the cover upon a side edge thereof. The holder is adapted to be formed from a blank of material by a single stamping operation, thus effecting the utmost simplicity and economy of construction, 70 while the formation of the slots in the body of the material provides a rigidity of the tongues adjacent thereto, which prevents bending or injury of the holder in its use and provides means for holding the box-cover at a 75 predetermined angle.

It will be obvious that changes may be made in the details of construction and configuration without departing from the spirit of the invention as defined by the appended claims. 80

Having described my invention and set forth its merits, what I desire to claim and secure by Letters Patent is—

1. A box-cover holder comprising a single plate having cover-engaging means at one end 85 and a plurality of box-engaging means at the opposite end adapted for independent engagement with a box.

2. A box-cover holder provided at one end with a cover-engaging slot having tongues at 90 opposite sides thereof bent away from the body of said holder and a plurality of box-engaging slots at the opposite end of the holder disposed in different positions relative to the cover-engaging slot.

3. A box-cover holder provided with a plurality of slots at one end having tongues upon each side thereof to adjustably engage the edge

- 2
- of a box, and a slot at the other end of said holder having tongues at each side thereof bent away from the body of said holder to engage and hold the cover to said box.
- 5   4. A box-cover holder comprising a curved plate provided with a plurality of slots at one end having tongues upon opposite sides thereof adapted to adjustably fit the edge of a box and a slot at the opposite end of the 10 holder having tongues at opposite sides there-

of bent away from the body of said holder in a curved line to engage the cover of said box.

In testimony whereof I have signed my name to this specification in the presence of two witnesses.

WILLIAM HENRY KIDDER.
